UNITED STATES PATENT OFFICE.

LUTHER P. FRIESTEDT, OF CHICAGO, ILLINOIS.

METHOD OF RAISING SUBTERRANEAN RIVERS.

SPECIFICATION forming part of Letters Patent No. 762,042, dated June 7, 1904.

Application filed February 3, 1904. Serial No. 191,834. (No model.)

To all whom it may concern:

Be it known that I, LUTHER P. FRIESTEDT, a citizen of the United States, residing at Chicago, in the county of Cook and State of Illinois, have invented new and useful Improvements in Methods of Raising Subterranean Rivers, of which the following is a specification.

This invention relates to a method of and means for raising the water-flow of subterranean rivers and streams that the water may be used for irrigation, power, and other purposes.

It is a well-known fact that in certain sections of the country there are watercourses underground which never rise to the surface. Again, there are rivers and streams that flow above the surface throughout certain seasons of the year either from heavy rainfall or melting snows and then for the remainder of the season sink below the surface and percolate through the sand, gravel, and limestone stratum, leaving the natural level dry.

The object, therefore, of this invention is to provide a simple and durable arrangement whereby the watercourse may be permanently brought to the surface without the construction and maintenance of expensive engineering works.

In the drawings, Figure 1 is a transverse section through a river course and the geological formation of the earth stratum embodying the improvement. Fig. 2 is a plan of a wall composed of metal sheet-piling.

The sheet-piling sections entering into the construction of the wall or dam A will ordinarily be of the standard rolled form of beams; but any special form may be used. In this instance the ordinary channel-beam is preferably employed as being best adapted for this particular purpose.

B represents plain beam-sections, the alternating joining sections C being each provided with a pair of Z-irons D, riveted or otherwise rigidly secured thereto, as shown in Fig. 2. The free flanges 3 overlap the joining corner-flanged edges 4 of the beam piling-sections B and provide an edgewise-interlocking connec-

tion and prevent lateral displacement when the sections are being assembled and driven into place in a wall structure. The ordinary pile-driver is used in the operation of driving, the piling-sections telescoping together endwise as they are assembled.

Fig. 1 shows a wall or dam extending across a dry river-bed from one bank to the other. a may represent the line of a dry water-channel; b, the underground-flowing body of water; d, earthy stratum between water and bed-rock g, down to which the pile-sections are driven. The operation of driving may be started from either side, beginning with the shorter section and gradually increasing in length until the middle is passed and then gradually shortening until the last section is placed in position, in accordance with the curvature of the earth in the formation of the river bed or channel. The sections are driven into place one after the other in continuous order, the engaging edges fitting closely together and with the earthy matter that will work into the interstices soon forms a perfectly-tight joint through which no water can escape. The water must now rise to the level of the surface and can be conducted away for irrigation or used for other practical purposes.

The piling-sections may be of any desired lengths as will be necessary to reach hard-pan in preventing the water from running underneath.

This method may also be followed in bringing underground rivers and streams to the surface that have never flowed above ground and the course of which are not indicated by a dry channel or bed. The underground streams are sometimes very wide and shallow; but the ease and facility with which the wall of sheet-piling may be continued to any extent in covering a wide range of territory is apparent. Wings may also be extended from the walls at any desired angle or a complete inclosure constructed and then excavated out to form a natural reservoir or basin for storage purposes. No excavating or other preliminary work is required preparatory to driving the piling into place.

Having thus described my invention, what I claim, and desire to secure by Letters Patent, is—

1. The method herein set forth of elevating 5 subterranean rivers to the surface, which consists in driving joining sheet-piling sections down through the earth to bed-rock and forming a solid wall transversely to the running direction of a watercourse.
- 10 2. The method herein described of bringing underground rivers and streams to the surface which consists in forcing sheet-piling section by section down through the earth to bed-rock across the line of a watercourse, said 15 piling-sections being loosely interlocked edge-wise and forming a continuous wall structure.

3. The method herein described of raising underground rivers and streams to the surface, which consists in the employment of metal beam-sections assembled edgewise 20 against lateral displacement and driven into the earth to a depth below that of the watercourse and forming a solid wall structure bisecting the same.

In testimony whereof I have signed my name 25 to this specification in the presence of two subscribing witnesses.

LUTHER P. FRIESTEDT.
